F. H. BRADEN

MAIL CARRIER'S BAG HOLDER

Filed Aug. 28, 1923

Fig. 1.

Inventor
Frank H. Braden.

By Grace C. Braden

Attorney

UNITED STATES PATENT OFFICE.

FRANK HENRY BRADEN, OF RAPID CITY, SOUTH DAKOTA.

MAIL-CARRIER'S-BAG HOLDER.

Application filed August 28, 1923. Serial No. 659,849.

To all whom it may concern:

Be it known that I, FRANK H. BRADEN, a citizen of the United States, residing at Rapid City, in the county of Pennington, State of South Dakota, have invented certain new and useful Improvements in Mail-Carriers'-Bag Holders; and I do hereby declare the following to be a full, clear, and exact description of the invention, such as will enable others skilled in the art to which it appertains to make and use the same.

This invention relates to new and useful improvements in supporting and carrying devices, and particularly to devices of this character which are especially adapted for use in connection with the bags used by mail carriers.

One object of the invention is to provide a novel and improved harness by means of which the bag is supported on both of the shoulders of the person, and the weight evenly distributed to both shoulders.

Other objects and advantages will be apparent from the following description when taken in connection with the accompanying drawing.

In the drawing:

The figure is a perspective view of a carrier's mail bag, equipped with the supporting harness, and showing the position of the parts when in use.

Referring particularly to the accompanying drawing, 10 represents the bag which has the usual rings 11 secured to its upper edge, and to which are connected the ends of the adjustable strap 12, and which strap is arranged to be passed over the shoulder of the carrier. A suitable pad is carried by the intermediate portion of the strap 12, and receives the strap slidably therethrough, said pad being shown at 13. Arranged to rest on the other shoulder of the carrier is a similar pad 14, and to the opposite ends of this pad are connected the straps 15, which have the snap hooks 16 for engagement with the auxiliary rings 17, secured to the wall of the bag, next to the carrier's body, and adjacent the opposite sides of the bag. These latter rings 17 are secured to the bag at points a suitable distance below the upper edge of the bag. The straps 15 are connected to the ends of the shoulder pad 14 by means of rings 18, and connected to these rings are the snap hooks

19 carried by the ends of an adjustable strap 55 20, which passes beneath the arm on which the pad 14 rests. Secured to the opposite ends of the shoulder pad 13 are the straps 21 which are adjustably connected with the snap hooks 22, and which hooks are engaged with the rings 18. The straps 21 pass across the chest and back of the carrier, and hold the shoulder pads 13 and 14 properly spaced apart, and being adjustable, can be regulated to suit the size of the person of 65 the wearer.

By properly adjusting the straps 15, and the straps 21, the weight of the bag can be brought to bear equally on the two shoulders of the carrier. By reason of the fact 70 that the pad 13 is connected to the upper edge of the bag, and the pad 14 is connected to the bag at a level below that of the first attachment, the pull of the straps 12 and 15, will be equalized, and the carrier 75 permitted to stand erect without effort, in spite of the fact that the weight of the bag may be great. The strap 20 prevents the bag pulling over toward one side. By this construction the carrier does not need to 80 shift the bag from one shoulder to the other, as in the case of the ordinary carrier device, where the entire weight of the bag is supported from one shoulder.

The two pads being connected to different 85 parts of the bag, support the bag independently of each other.

What is claimed is:

The combination with a mail carrier's bag having attaching means on the upper 90 edge and attaching means on one wall at a distance below the first attaching means, of pads for engagement across the shoulders of a carrier, straps connecting the ends of one pad to the first attaching means, straps 95 connecting the ends of the other pad with the other attaching means, a strap connected to the ends of the second pad for engagement beneath the arm of the wearer, and straps connecting the ends of the second pad 100 with corresponding ends of the first pad.

In testimony whereof, I have affixed my signature, in the presence of two witnesses.

FRANK HENRY BRADEN.
